(57) **CLAIM**

The ornamental design for a submersible water toy, as shown and described.

DESCRIPTION

FIG. 1 is a perspective view of a submersible water toy;

FIG. 2 is a top view of the submersible water toy illustrated in FIG. 1;

FIG. 3 is a bottom view of the submersible water toy illustrated in FIG. 1;

FIG. 4 is a left side view of the submersible water toy illustrated in FIG. 1; the right side view being a mirror image of the left side view; and,

FIG. 5 is a front end view of the submersible water toy illustrated in FIG. 1; the rear end view being a mirror image of the front end view.

The portion of the article depicted in broken lines is for illustrative purposes only and forms no part of the claimed design.

1 Claim, 2 Drawing Sheets
